R. B. BUTTERBAUGH

PNEUMATIC TOOL

Filed April 25, 1921

Patented Feb. 5, 1924.

1,482,543

UNITED STATES PATENT OFFICE.

RALPH B. BUTTERBAUGH, OF MINNEAPOLIS, MINNESOTA, ASSIGNOR TO REUBEN E. HAUSER, OF MINNEAPOLIS, MINNESOTA.

PNEUMATIC TOOL.

Application filed April 25, 1921. Serial No. 464,481.

To all whom it may concern:

Be it known that I, RALPH B. BUTTERBAUGH, a citizen of the United States, residing at Minneapolis, in the county of Hennepin and State of Minnesota, have invented certain new and useful Improvements in Pneumatic Tools; and I do hereby declare the following to be a full, clear, and exact description of the invention such as will enable others skilled in the art to which it appertains to make and use the same.

My invention provides what is herein designated as a pneumatic tool but which, in a broader sense, is a portable power device including a motor and means for operating, at will, various different kinds of tools with either continuous rotary or oscillatory movements. Generally stated, the invention consists of the novel devices and combinations of devices hereinafter described and defined in the claims.

The motor is preferably a rotary pneumatic motor mounted on a casing having suitable handles or hand pieces and connected to a source of compressed air supply through a flexible tube. The rotor of the motor has a projecting driving shaft to which a driving wheel, drill, buffing wheel or other tool, that should be driven with a rotary motion, is adapted to be applied, preferably by screw-threaded engagement. Mounted in the casing and surrounding the driving shaft of the motor is an oscillatory driving sleeve that receives its oscillatory motion from the motor preferably through a cam and a co-operating lever of novel construction and arrangement, and which cam and lever are located within the casing. The oscillatory driving sleeve projects from the casing and a screw driver or other tool, that requires oscillatory motion, is adapted to be secured thereto at will.

In the above arrangement, when the motor is in action the driving shaft of the motor will be driven in a continuous direction while the sleeve will be continuously oscillated around the running shaft. Hence, the projecting ends of the shaft and sleeve afford means to which, in the first instance, tools requiring rotary motion may be applied, and, in the second instance, to which tools requiring oscillatory motion may be applied, and, as is evident, the substitution of rotary for oscillatory tools may be made without requiring disconnection or adjustment of any

of the running or motion-transmitting elements of the device.

Preferably, the casing has two hand pieces, one in line with the axis of the motor shaft and the other radiating therefrom, and the latter is made hollow with the introduction of air to the motor and is equipped with a thumb-actuating controlling valve. This arrangement permits the tool to be held properly to its work and guided by the hands of the operator and the speed of the motor also to be readily controlled.

In the accompanying drawings, which illustrate the invention, like characters indicate like parts throughout the several views.

Referring to the drawings:

Fig. 1 is a side elevation with some parts broken away and some parts sectioned, showing the improved tool or power device and showing a grinding wheel applied to the motor shaft;

Fig. 2 is a transverse section taken on the line 2—2 of Fig. 1, but showing a screw driver applied to the oscillatory sleeve of the device;

Fig. 3 is a horizontal section on the line 3—3 of Fig. 1; and

Fig. 4 is a horizontal section on the line 4—4 of Fig. 2.

The casing, as shown, is made up of two shell sections 5 and 6, separated by a partition plate 7, said three elements, at their margins, being connected by machine screws 8 or the like. The partition 7 divides the casing into two chambers 9 and 10, the former of which affords a cylindrical chamber for the rotary head 11 of the pneumatic motor. This head or rotor 11 of the motor is of cylindrical form, is of less diameter than the interior of the chamber 9 and runs in contact therewith at one point marked *y* on Fig. 3; and here it may be noted that the cylindrical wall of the shell 5, in the vicinity of said point of contact *y*, has a slightly yielding segmental portion 12 that is adapted to be adjusted by a screw 13 so as to compensate for wear and always prevent leakage of air past the contact point *y*.

The rotor 11 has radially movable spring-pressed propelling blades 14, and it is provided with a driving shaft 16 that projects down through the bottom of the shell 6 and, as shown, is terminated in a threaded end 17 onto which the internally threaded sleeve 18 of a rotary tool, such as a grinding wheel

19, is adapted to be screwed, as shown in Fig. 1.

5 Adjacent to the rotor 11, the motor shaft 16 is journaled in the partition 7, preferably by a ballbearing 20. The numeral 21 indicates a thrust-acting ballbearing interposed between the upper face of the rotor 11 and the top of the case shell 5. Said shell 5, above the bearing 21 and in approximate 10 alignment with the driving shaft 16, has a hand piece 22 in the form of a knob.

15 At one side, the shell 5 is provided with a radially projecting hollow handle 23, to the outer end of which a flexible compressed air supply tube 24 is attached. The inner end of the hollow hand piece 23 opens into the interior of the chamber 9 through an admission port 25, see Figs. 1 and 3, and, at approximately a diametrically opposite point, 20 said chamber 9 is provided with discharge ports 26.

25 The admission port 25 is normally closed by an axially movable pressure-seated valve 27 mounted in the hand piece 23 and arranged to be opened more or less, at will, by the beveled inner end of a thumb-actuated cam plunger 28 mounted in the hand piece 23, as shown in Fig. 1. The valve 27 is of the well known type which has a stem loosely 30 fitting the port 25 so that there will be a passage of compressed air when said valve 27 is contracted.

35 The oscillatory driving sleeve 29 is journaled on the motor shaft 16 and in the lower wall of the shell 6. At its upper or inner end, the oscillatory sleeve 29 has a projecting crank arm 30 provided at its free end with a crank pin 31. The numeral 32 indicates a lever pivoted at 33 to a lug 34 depending from the partition 7. This lever 32 is preferably in the form of a yoke that has an elongated interior or slot with which it 40 engages an operating cam in the form of an eccentric 35 carried by the motor shaft 16. 45 At its free extremity, this yoke-like lever 32 has a notch 36 in which works the crank pin 31 of the lever 32.

50 As is evident, when air is admitted to the chamber 9, the rotor or head 11 of the motor, and the motor shaft 16, will be rotated in the direction of arrows marked on Fig. 3, so that any tool or device attached to the threaded or outer end of the motor shaft 16 will be rotated in a constant direction. However, 55 the driving sleeve 29 will be continuously oscillated on the shaft 16 so that a screw driver or any other tool, attached to the lower or outer end thereof, will be continuously oscillated.

60 In Fig. 2, the numeral 37 indicates a screw driver which has a tubular stem 38, the upper end of which is adapted to be telescoped onto the end of said sleeve 29 and is split and provided with lugs 39, which,

65 by a co-operating screw 40, adapt the split end of said sleeve to be securely clamped to said driving sleeve 29.

70 The screw driver attachment is especially adapted for use in grinding engine valves to their seats and, in this use, the device affords an extremely efficient valve grinder.

75 When a drill chuck or the like is applied to the rotary shaft 16, a drill is adapted to be held thereby and the device then affords a highly efficient portable power-driven drill. 80 Of course, the device is capable of a very large range of use, by the substitution of various different kinds of tools, either rotary or oscillatory, in the manner described. Moreover, the device is simple and of comparatively small cost.

85 What I claim is:

1. A portable power device comprising a casing, an oscillatory sleeve projecting from said casing, a rotary motor-driven shaft 90 mounted in said casing and projecting through said sleeve, said sleeve and shaft being arranged to operate different tools, a lever pivoted within said casing and connected to said sleeve for oscillating the same, and an eccentric element carried by said shaft and directly operative on said lever to oscillate the latter.

95 2. A portable power-driven device of the kind described comprising a casing, an oscillatory sleeve projecting from said casing, a rotary motor-driven shaft mounted in said casing and projecting through said sleeve, said sleeve and shaft being adapted to operate different tools, an eccentric cam directly 100 carried by said shaft within said casing, a yoke-like lever embracing and directly engaged by said cam and pivoted within said casing at one end, said sleeve having an arm to which the other end of said lever is directly pivoted.

105 3. A portable power device of the kind described comprising a casing formed with two chambers, a pneumatic motor, the rotor of which works within one of the compartments of said casing and is provided with a driving shaft projected from said casing and adapted to carry a rotary tool, a sleeve surrounding said shaft and projecting from said casing and adapted to carry an oscillatory tool, a crank arm on the inner end of said sleeve, a lever pivoted within said casing and connected to said crank arm, and a cam on said driving shaft operative on said lever to oscillate the same, said lever being 110 in the form of an endless yoke that embraces said cam and, at its free extremity, has a slot that engages a crank pin provided on the end of the arm of said oscillatory sleeve.

115 120 In testimony whereof I affix my signature.

RALPH B. BUTTERBAUGH.
